HIGHWAY CROSSING SIGNAL

Filed March 31, 1925

2 Sheets-Sheet 2

UNITED STATES PATENT OFFICE.

CARL R. GRAVES, OF CLARION, IOWA.

HIGHWAY-CROSSING SIGNAL.

Application filed March 31, 1925. Serial No. 19,689.

To all whom it may concern:

Be it known that I, CARL R. GRAVES, a citizen of the United States, residing at Clarion, in the county of Wright and State 5 of Iowa, have invented certain new and useful Improvements in Highway-Crossing Signals, of which the following is a specification, reference being had to the accompanying drawings.

10 This invention relates to signals to be used where a highway crosses a railway, and particularly to certain improvements upon the semaphore signal and actuating devices which are illustrated in my Patent #1, 15 506,630 granted on the 26th day of August, 1924.

One of the objects of the present invention is to provide a signal particularly adapted to be used in connection with the 20 actuating device for railway crossing signals illustrated and described in my pending application Serial #7,072, filed February 5, 1925.

A further object of the present invention 25 is to provide a semaphore and signal mechanism which will permit the semaphore arm to drop to its clear position no matter how fast the train which actuates the signal is traveling, and in this connection to provide 30 a semaphore arm and connected signal which will drop no faster when under the action of a fast train than it will under the action of a slow train, or in which the semaphore arm is controlled entirely by the action 35 of gravity and, therefore, will only drop as fast as the force of gravity will permit.

A still further object is to provide an operating mechanism for this signal which is so constructed that high speed trains can 40 put the signal to clear position without causing unnecessary strain on the semaphore arm and the signal mechanism carried thereby.

Another object is to provide a semaphore 45 arm which is urged to its danger position by a spring.

Other objects have to do with the details of construction and arrangement of parts as will appear more fully hereinafter.

50 My invention is illustrated in the accompanying drawings, wherein:—

Figure 1 is an elevation of a highway signal constructed in accordance with my invention, showing in dotted lines the safety 55 position of the signal;

Figure 2 is a longitudinal sectional view through the lamp housing;

Figure 3 is a front elevation of the bell crank 34;

Figure 4 is a fragmentary elevation of the 60 link 41;

Figure 5 is a diagrammatic plan view of a track and the connections between the operating mechanism of the signal and the train actuated devices along the track; 65

Figure 6 is a perspective view of the bell crank levers for operating the lever controlling the setting of the signal.

Referring to these drawings, 10 designates the signal mast and 11 the semaphore arm 70 which is pivoted to the mast at 13. Engaging the upper end of the signal mast 10 is a support 12 for the light box 21 within which lanterns are to be disposed. This housing 21 has two bull's-eyes 18 and 19 respectively, the bull's-eye 18 having preferably a red glass with the word Stop formed thereon, while the other bull's-eye may be made of green glass or clear glass with the word Go indicated thereon. Mounted upon 80 the semaphore arm 11 is an arm 14 which extends out at an angle thereto and is provided with a shield 15 which is adapted to be disposed over either of the bull's-eyes 18 or 19, and this arm 14 is pivoted upon the 85 pivot 13 and extends forward, as at 16, and is operatively connected or bolted to the signal arm or semaphore 11. The rear end of the semaphore arm 11 is counterweighted at 17, but this counterweight is less in weight 90 than the weight of the semaphore arm 11 so that the semaphore arm will descend under gravity when it is released.

Pivottally connected to the semaphore arm 95 is a link 22. This link in turn is pivotally connected at 23 to a hollow tubular sleeve 24 which fits over and has telescopic engagement with a vertical rod 25 which is mounted in guides 26 on the post 10. Between the lower guide 26 and the upper guide 26 100 a coiled spring 27, surrounds this rod, the coiled spring bearing at its lower end upon the lower guide 26 and at its upper end against a shoulder or collar 28 carried by the rod 25. Thus this spring acts to urge the 105 rod 25 upward. Removably pinned to the lower end of the rod 25 below the lower bracket 26 is a shank 29 which is rectangular in cross section and which passes at its lower end through a guide 30 attached to the face 110

of the mast 10. This shank 29 upon its inner face is recessed at 31 adjacent its upper end so as to form a keeper for a bolt, as will be later stated. The lower end of this shank beyond the guide 30 is reduced and pivotally connected to a rod 32.

Mounted upon the opposite face of the mast 10 from the member 29 is an outwardly projecting bracket 33, and pivotally mounted upon this bracket is a member 34 which constitutes a bell crank. This member 34 is pivoted intermediate its ends to the bracket and at its upper end is bent inward or toward the mast 10 and the lower portion 15 of this bell crank is bifurcated or forked at 35. Mounted upon the mast 10 is an approximately U-shaped bracket 36 which constitutes a guide for the outer end of a latch bolt 37. This latch bolt passes through an opening in the mast 10 and through a guide plate 38 attached to the face of the mast, and this last bolt is adapted to engage in the recess 31 to thereby lock the rods 25 and 32 and the member 29 in their lowered position. A spring 39 acts to force the bolt outward. The rear end of this bolt has a transversely extending pin 40 and the rear end of the bolt is embraced by the fork 35 and the curved lower end of the fork 35 engages behind this pin 40. The upper end of the bell crank lever 34 is connected to a link composed of two parallel members 41 spaced apart to pass over the brackets 33 and 36, and this link extends downward and is riveted at its lower end to a rod 42.

With the construction so far described, it is obvious that assuming the signal arm to be depressed, the rod 25 under these circumstances is depressed, as is the member 29, and the bolt 37 will engage in the recess 31. If now a train approaches a crossing and reaches a certain predetermined position, it engages a member which, as will be hereafter described, exerts a strain upon the rod 41. This will draw downward on the rod 42 and yoke 41 and this will pull downward upon the upper portion of the bell crank lever 34, causing its lower end to retract the latch 27. This will release the latch from its engagement with the keeper 31 on member 29, whereupon the spring 27 bearing against the shoulder 28 will urge this rod 25 upward, carrying with it the sleeve 24 against which the upper end of the rod abuts and shifting the semaphore to its raised or danger position and shifting the shield 15 over the bull's-eye 19 so that the bull's-eye 18 is unobscured and the word Stop is displayed. When the last car of the train has passed the crossing, as is fully described in my application filed February 5, 1925, Serial #7,072, an actuating device will, through mechanism to be later described, pull upon the rod 32, drawing downward on rod 32, member 29, and

rod 25. No matter how fast the train is going these parts will shift downward with rapidity and will be caused by the spring-projected latch 27 engaging the keeper 31, but this withdrawal of the rod 25 releases the signal arm 11 and the signal arm will then descend more or less slowly by gravity. The speed of the downward movement of the signal arm depends entirely upon the difference between the weight of the arm 11 and the counterweight 17. If this difference in weight is great, the signal arm will descend to its safety position very rapidly. If, on the other hand, the difference is slight it will descend very slowly. Therefore, it will be obvious that the speed of descent of this arm 11 may be very readily controlled. As the arm 11 descends, it carries the shield 15 from in front of the bull's-eye 19 to a position in front of the bull's-eye 18, the word Stop is obscured and the word Go, which is on the bull's-eye 19, is exhibited.

It will be understood that the pull upon the rod 42 occurs as a train reaches a certain distance from the highway crossing, as fully set forth in my patent above referred to and the application above referred to, and that the semaphore arm remains in its danger or stop position until the last car of the train has passed the crossing, whereupon, through mechanism illustrated and described in the patent before referred to and in the application above noted, the rod 32 is pulled, which withdraws the support for the sleeve 24 and the semaphore descends to its safety position.

Certain mechanism for connecting the rods 32 and 42 to the actuating devices disposed along the track is illustrated in my patent and this construction, as will be seen from Figures 5 and 6, comprises a pair of levers 43 and 44, the lever 43 being pivoted upon a pivot pin 45 mounted upon a supporting stand 46, and the lever 44 being mounted upon a pivot pin on a stand 47. The lower face of each of the levers 43 and 44 is provided with a transversely extending pin 48. Mounted upon the same stand 46 and upon the same pivot 45 are two bell crank levers 49 and 50, it being understood that there are a pair of these bell crank levers for each of the levers 43 and 44. The bell crank lever 49 for the lever 43 is connected to a rod 51, while the bell crank lever 50 for the lever 43 is connected to a connecting rod 52. The bell crank lever 49 for the lever 44 is connected to a rod 53, while the bell crank lever 50 for the lever 44 is connected to a rod 54. The connecting rods 51 and 52 extend to bell cranks 55 and 56 which have connecting rods 57 and 58 extending along the track, these rods connecting to the setting levers which are disposed beside the track and actuated by the arrival of a train approaching the crossing.

- The rods 53 and 54 are connected to bell crank levers 58 and 59, which in turn are connected to rods 60 and 61 which connect to the depressible restoring levers mounted 5 at the side of the track and actuated when the last car has passed the highway crossing.
- The actuating devices whereby pull is exerted upon these rods 57, 60 and 61 form the subject-matter of my application filed February 5, 1925, Serial #7,072, previously referred to, and these levers are shown diagrammatically in the present application and the setting levers, as they may be called, are designated 62, while the levers 10 which restore the signal to its safety position or release the signal are designated 63. As certain levers for this purpose are fully shown in my patent before referred to and the preferable form of these levers and their 15 connections are fully shown in the application before referred to, it is not believed necessary to illustrate these levers or the particular connections of the levers to the rods 57, 60 and 61.
- 20 It will be understood that assuming a single track is used, the setting levers 62 will be disposed at a considerable distance up and down the track so that as a train approaches the crossing from either direction the front wheels of the train will operate these levers and in doing so will exert a pull either upon the bell crank 55 or the bell crank 56. Assuming that a pull is exerted upon the bell crank 55 and that the 25 signal is in its safety or lowered position, then the operation of the bell crank 55 will cause a pull upon the rod 51. This will depress the bell crank lever 49 for lever 43 and cause the depression of this lever 43 without, however, affecting the bell crank 30 lever 50. The depression of the lever 43 will cause a pull to be exerted upon the rod 42, releasing the latch bolt 37 from its engagement with the member 29, and the 35 spring 27 will shift the rod 25 upward until the collar 28 reaches the bracket 26. The upward movement of the rod 25 will raise the sleeve 24 and lift the signal to its danger position, as before described. A like 40 movement will be transmitted to the rods 32 and 25 and to the signal upon the approach of a train from the other direction which will operate the bell crank lever 50. The train moves onto and across the 45 crossing and as soon as the last car has passed the crossing, the last wheels of the car will act to depress the restoring lever 63 and this will exert a pull upon the corresponding rod 60 or 61 which will shift 50 the corresponding bell crank lever 58 or 59. This will exert a pull upon one of the rods 53 or 54 and the corresponding bell crank 54^a or 50^a will be depressed, drawing down the lever 44 and thus exerting a pull upon 55 the rod 32. This rod 32, therefore, will be

depressed against the action of the spring 27 and when it reaches the full extent of its downward movement the bolt 37 will snap into place, locking this rod 32 and the part 29 and the rod 25 depressed and permitting the signal to descend by gravity, as before described. Springs 64 act to return the levers 49 and 50 and 49^a and 50^a to their initial positions.

It will be seen that the mechanism which I have described heretofore is the same in principle as the mechanism which was described in my prior application and patent, but that it differs from the mechanism illustrated in my patent by the fact that in the patent the signal was pulled to its safety position by the depression of an actuating device or setting lever and did not drop to its safety position by the action of gravity, and in my prior patent this signal was held in its depressed position by means of a spring latch. When this latch was released through the action of the restoring levers mounted upon the track, a spring 80 acted to shift the semaphore to its danger position. Inasmuch as the semaphore was shifted to its danger position through a number of links and levers, there would be a great deal of inertia and as a consequence there would be a great deal of strain upon the semaphore signal. It would drop too suddenly and quickly and it was to obviate this difficulty that I have provided the present construction where the semaphore arm is not directly connected to the actuating 85 means but is pushed upward into its danger position by a spring and is shifted to its safety position entirely by the action of gravity.

It is to be noted that in this construction the spring 27 acts only to force upward on the parts 25, 29, 32 and the bell crank 44 and that the upward movement does not in any way affect the levers 49^a or 50^a nor the links extending therefrom over to the railway rails and up the track, and that, on the other hand, the spring 39, when it projects the bolt 37, only has to move the parts 34, 41 and 42 and the lever 43. It will, therefore, be seen that the levers 43 and 44 and the bell crank levers 49 and 50 and 49^a and 50^a are very necessary parts of the stand itself, as without the use of these bell crank levers 44, 43, 49, 50 and 50^a the signal would not properly operate as it would be impossible for the springs 27 and 39 to act against the inertia of a long series of connecting rods, levers, etc., extending up and down the track.

While I have illustrated a construction which I have found to be particularly convenient and effective, I do not wish to be limited to the details of construction illustrated as these might be varied in many ways without departing from the spirit of

the invention. Neither do I wish to be limited to the use of the signaling mechanism and its stand in connection with the exact system of actuating devices illustrated in my application #7,072, filed February 5, 1925, nor the construction illustrated in my patent, though this signaling mechanism has been particularly designed with relation to the construction illustrated in my pending application.

I claim:

1. A crossing signal for railways including a support, a signal arm mounted on said support and urged by gravity to a lowered position, a vertically shiftable member adapted, when raised, to hold the signal arm raised, train-actuated means for shifting the member downward to thereby permit the signal arm to drop to its safety position, means urging the shiftable member upward, means latching the shiftable member in its lowered position, and train-actuated means for releasing said latch.

2. A crossing signal for railroads including a support, a signal arm mounted on the support and urged to a lowered position, a vertically shiftable member separate from but disposed to engage the arm in its upward movement and thereby lift the arm, train controlled means for lifting the member and thereby lifting the arm to a raised position, and train controlled means for lowering the member to thereby permit the arm to drop to its lowered position.

3. A crossing signal for railroads including a support, a signal arm mounted on the support and urged to a lowered position, a vertically shiftable member separate from but disposed to engage the arm on its upward movement and lift the arm, a spring urging said member upward, train controlled means for lowering the member, a latch holding the member lowered, and train actuated means for releasing said latch to permit the member to raise said arm.

4. A crossing signal for railways including a support, a signal arm pivotally mounted upon the support and urged by gravity to a lowered position, a vertically shiftable member separate from but disposed to engage the arm on its upward movement and lift the arm to a danger position, a spring urging said member upward, a spring actuated latch adapted to hold the member lowered, and train controlled means for releasing said latch.

5. A crossing signal for railways including a post, a signal arm pivotally mounted upon the post and urged by gravity to a lowered or safety position, a vertically disposed rod mounted upon the post, a spring urging said rod to a raised position, a latch holding the rod in a lowered position, a member mounted upon the arm and extending parallel to the rod, the member and rod

having telescopic limited movement, train controlled means for releasing the latch, and train actuated means for lowering said rod against the action of the spring.

6. A crossing signal for railroads including a vertical mast, a signal arm pivotally mounted on the mast and urged by gravity to a lowered position, a vertically shiftable member mounted upon the mast and separate from but disposed to operatively engage and lift the arm on its upward movement and on its reverse movement to permit the arm to descend by gravity, a spring urging said member upward, a latch holding the member lowered against the action of the spring, train controlled means for releasing the latch to thereby permit the rod to raise the signal arm to its danger position, and train controlled means for lowering said rod.

7. A crossing signal for railroads including a vertical mast, a signal arm pivotally mounted on the mast and urged by gravity to a lowered position, a vertically shiftable member mounted upon the mast and separate from but disposed to operatively engage and lift the arm on its upward movement and on its reverse movement to permit the arm to descend by gravity, a spring urging said member upward, a latch holding the member lowered against the action of the spring, train controlled means for releasing the latch to thereby permit the rod to raise the signal arm to its danger position, and train controlled means for lowering said rod, the signal arm carrying a vertically movable socket and the upper end of the rod being inserted in said socket.

8. The combination with a line of track and a siding, of a highway crossing signal disposed along the track and including a signaling member urged to a safety position, a vertically shiftable member resiliently urged in a direction to lift the signaling member to a danger position, a latch holding the vertically shiftable member in its lowered position, train operated means on both sides of the railway crossing and remote from the signal for releasing the latch to permit the signal to shift to danger position upon the approach of a train, train operated means on both sides of and adjacent the signal operatively connected to the vertically shiftable member to cause the downward movement of the vertically shiftable member when a train engages said train operated means, each of said means being independently operable and each being operated only by a train receding from the signal.

9. A crossing signal for railroads including a mast, a signal arm pivotally mounted upon the mast and movable downward by gravity, a vertically shiftable member mounted upon the mast below the signal

arm, a spring urging said member upward, a member carried by the signal arm and having limited telescopic engagement with the first named member whereby to cause
5 the first named member to lift the signal arm upon an upward movement but permit the signal arm to descend by gravity when the first named member is lowered, a spring urging the first named member upward, a
10 latch bolt holding the first named member in its lowered position, a spring urging the latch bolt into engagement with the member, a bell crank lever mounted upon the mast and having one end thereof engaged
15 with the latch bolt, train controlled means

operated upon the approach of a train toward the crossing for actuating said connection to the bell crank lever to thereby release the latch bolt and permit the upward movement of the first named vertically movable member and the lifting of the signal arm to danger position, and means actuated by a recession of the train from the crossing for retracting the first named member against the action of said spring to thereby permit the signal arm to descend by gravity.

20 In testimony whereof I hereunto affix my signature.

CARL R. GRAVES.
